US0D1041300S

(12) **United States Design Patent** (10) **Patent No.:** **US D1,041,300 S**
(45) **Date of Patent:** **** Sep. 10, 2024**

(54) **BRACKET**

(71) Applicant: **Hope Enterprises LLC**, St. Augustine, FL (US)

(72) Inventor: **Richard E. Hersey, Jr.**, St. Augustine, FL (US)

(73) Assignee: **HOPE ENTERPRISES LLC**, St. Augustine, FL (US)

(**) Term: **15 Years**

(21) Appl. No.: **29/937,501**

(22) Filed: **Apr. 15, 2024**

Related U.S. Application Data

(62) Division of application No. 29/839,856, filed on May 24, 2022, now Pat. No. Des. 1,022,682.

(57) **CLAIM**

The ornamental design for a bracket, as shown and described.

DESCRIPTION

FIG. 1 is a front perspective view of a bracket;

FIG. 2 is a rear perspective view thereof;

FIG. 3 is a top view thereof;

FIG. 4 is a bottom view thereof;

FIG. 5 is a side view thereof;

FIG. 6 is a front view thereof;

FIG. 7 is a rear view thereof; and,

FIG. 8 is an in-use view thereof.

The broken lines of FIGS. 1-7 are included for the purpose of illustrating portions of the bracket and form no part of the claimed design. The additional broken lines of FIG. 7 are included for the purpose of illustrating environmental structure and form no part of the claimed design.

1 Claim, 6 Drawing Sheets
